UNITED STATES PATENT OFFICE

CHARLES W. LOGAN, OF KENMORE, NEW YORK

DESIGN FOR AN ELECTRIC HEATER

Application filed June 30, 1930. Serial No. 36,234. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for an Electric Heater, of which the following is a specification, reference being had to the accompanying drawing, forming part thereof.

In said drawing:

The only figure is a perspective view of an electric heater embodying my new design, the back of the heater which is not shown being substantially plain.

I claim:

The ornamental design for an electric heater substantially as shown and described.

CHARLES W. LOGAN.
